UNITED STATES PATENT OFFICE.

HARRY H. LYON, OF NEW ALBANY, AND WALTER W. LYON, OF TOWANDA, PENNSYLVANIA.

LOCK.

964,990.

Specification of Letters Patent. Patented July 19, 1910.

Application filed April 7, 1909. Serial No. 488,464.

To all whom it may concern:

Be it known that we, HARRY H. LYON and WALTER W. LYON, citizens of the United States, residing at New Albany and To-5 wanda, respectively, in the county of Bradford and State of Pennsylvania, have invented certain new and useful Improvements in Locks, of which the following is a specification.

10 This invention relates to improvements in locks, and more particularly to automatic controlling means therefor.

The primary object in view is the control of a lock from a distance relative to varying 15 conditions, as the control of a toilet door lock relative to the movement of a car.

With this and further detail objects in view as will in part be set forth and in part become obvious, the invention comprises cer-20 tain novel constructions, combinations and arrangements of parts as hereinafter disclosed and claimed.

In the accompanying drawings,—Figure 1 is a view in side elevation of a fragment of 25 a car axle illustrating in elevation a governor in its relation to the lock controlling switch together with the lock, the casing of the latter being shown in section for disclosing interior structure. Fig. 2 is an edge 30 view of one of the sections of the governor collar detached, a section of the switch-throwing collar being seen in dots. Fig. 3 is a plan view of one of the governor weights and connected parts detached. Fig. 35 4 is a detail, transverse section through one of the slide rack bars. Fig. 5 is a detail, perspective view of the washer of one of the governor weight retaining bolts. Fig. 6 is a horizontal, detail section taken along the 40 upper edge of the casing and showing in top plan the night latch slide, the upper end of the key actuated finger of the latch being seen in dots. Fig. 7 is a detail elevation of the knob operated parts, some of the 45 same being spaced for clearness of disclosure. Fig. 8 is a plan view of the hub engaging pawl. Fig. 9 is an end view thereof.

Referring to the drawings by numerals, 1 indicates an ordinary lock case into which 50 extends the squared hollow, knob shafts 2, 2, the inner end of each engaging a hub 3, and one of the hubs 3 being provided with a boss 4 rotatably mounted in a recess in the other hub. Each hub 3 is provided with an 55 outwardly extending boss 5 rotatably

mounted in the side walls of casing 1 in condition for retaining the hubs 3 in proper position. The squared shafts 2 are retained in place by securing bolts 6, 6, extending therethrough, and threaded into the respective hub 3, and the knobs are retained on the shafts 2, each by its usual retaining bolt engaging in one of recesses 7 formed in the respective shaft. 60

An ordinary latch 8 projects from the 65 edge of the casing 1, and at its inner edge pivotally engages an operating lever 9 normally retained by a spring 10 in condition for positioning the latch 8 at the outer limit of its movement. An upstanding 70 finger 11 projects from the upper end of lever 9 and lies along side the key hole 12, in position for being shifted by the key for drawing the latch 8 inwardly. The lever 9 is pivoted near its upper end, as at 75 13, and is provided with an arm 14 extending laterally from the upper end and arched as at 15 in the usual manner over the hubs 3, said hubs being provided each with a pair of shoulders 8' either of which 80 is adapted to engage the arm 14 and elevate the same when the respective hub is rocked or oscillated, the elevation of lever arm 14 swinging the lower end of the lever 9 inwardly, and thus retracting the latch 8. 85

A night latch 16 is pivoted as at 17' within the casing 1 and is provided with a pin 18' engaging a retaining spring 19' adapted to retain the latch at either extreme 90 of its movement. The lower end of the latch 16 is positioned for swinging to a point immediately above the free end of lever 14. A slide 17 is pivotally connected at one end to latch 16, and in its lower face near the other end is formed with a recess 18 terminating at its outer end in a shoulder 19. A pawl 20 is pivoted to slide 17 and pressed by spring 21 into position for having its free end extend past a portion of the recess 18, excess movement of pawl 20 being prevented by a retaining lug 22 projecting laterally from slide 17. Slide 17 is retained in position by lugs 17" and 23 extending laterally from the casing 1. Thus if the night latch is thrown with its upper end to the 105 right, that is with the lower end above lever arm 14, and a key is introduced through key hole 12 and revolved, the key will first strike shoulder 19 and throw the slide toward the left, thus swinging the latch 16 to 110

the released position and the further movement of the key will then retract latch 8.

A lug 24 extends inwardly from the rear edge wall of the casing 1, and a catch lever 25 is pivoted thereto, as at 26, the lever 25 being formed intermediate its length into an armature 27 disposed immediately above the electro-magnets 28, 28. The inner or free end of lever 25 is formed with laterally 10 extending projections 29, 29. Intermediate the length of the armature 27 are arranged eyes 31, 31, the upper one of which is engaged by a spring 32 normally maintaining the armature in an elevated condition. 15 When the lever 25 is so elevated, the upper projection 29 extends into a notch 33 in one of the hubs 3, such hub being thus retained against oscillation. As both projections 29 lie in the same vertical planes, one 20 of said projections will engage the notch 33 in one hub 3, and when the lever 25 is inverted the other projection 29 will be in position to engage the notch 33 of the other hub 3, so that the lock may be adjusted by a 25 mere inversion of the lever 25 to a right or left lock, or the same adjustment may be utilized for locking either the outside knob against operation or the inside knob against operation. Assuming that the lock is to be utilized 30 on the door of a toilet room of a car, the lever 25 will be positioned for having projection 29 engage the notch 33 of the outside hub 3. Obviously, when current is supplied to the magnets 28 and the armature 27 is thus 35 energized and drawn downwardly against the pressure of the spring 32, the outside hub or hub engaged by projection 29 will be free to oscillate, and for purposes of adapting the lock to railroad car toilets or 40 elsewhere where access is only desirable during transit, we provide a suitable electrical circuit 34 for the magnets 28, which includes a battery or other suitable source of electrical supply 35, and switch 36 adapted 45 at times to break the circuit, one member of the switch being carried by a lever 37 provided with a roller 38 depending contiguous to the axle 39 of the car.

A collar 40 is firmly clamped onto the 50 axle 39, being made up preferably of two semi-circular sections, as clearly seen in Fig. 2, which are clamped together by bolts 41 passed through flanges 42, 42, at the terminals of the respective sections. Obviously, the collar 40 may be otherwise constructed and secured in position. Each section 40 of the collar is provided with parallel outwardly projecting arms or lugs 42', 42', in which is journaled a shaft 43 carrying a segmental rack 44. Each rack 44 is an exact duplicate of the other, and each is provided with an arm 45 extending, when at rest, substantially parallel to the axle 39, and terminating at its free end in a 60 governor weight 46. Each arm 45 is pro-

vided with a concaved seat 47 having a transverse slot 48 through which extends an adjusting bolt 49 engaged by a retaining nut 50 preferably provided with the usual finger operating wings. A semi-cylindrical washer 51 is disposed between nut 50 and the seat 47 and snugly fits therein in position to rock when necessary to accommodate movement of the arm 45. The slot 48 of course is of sufficient length to accommodate lateral movement of bolt 49 during any rocking of the washer 51. The inner end of each bolt 49 is engaged by a restraining spring 52 which extends toward the axle 39 and engages an eye 53 fixed to a lateral projection 54 formed on the respective collar section. Beneath the inner ends of the arms or lugs 42' is formed the under-cut slide-way or groove 55, which extends throughout the length of the projection 54 and in which is slidably mounted the rack bar 56, which is formed with flanges 56', 56' corresponding to and snugly fitting within the under-cut portions of groove 55, rack bar 56 being thus held firmly against any twisting or lateral play and is guided in its longitudinal movement so as to reciprocate freely and easily. Each rack bar 56 is provided on its outer edge with teeth 56' meshing with the teeth 44' of the respective segmental rack 44. The ends of the rack bars 56 are fixed to an annular collar 57 which surrounds and is freely shiftable longitudinally of the axle 39, the inner edge of the collar 57 being spaced from the axle so as to obviate friction, the relative position of the collar 57 being indicated in dots in Fig. 2. The collar 57 is preferably made of two semi-circular sections secured together by bolts 58 passed through lugs 59, 59, extending rearwardly from the terminals of the sections of collar 57. The front face of the collar is thus left continuous and smooth and presents an annular surface which is adapted to be shifted bodily 100 backward and forward along the axle 39 according to the speed of revolution of the axle. As disclosed in Fig. 1, the roller 38 is disposed contiguous to and in the path of movement of the collar 57, so that when the rotation of axle 39 ceases, and the arms 45 are retracted by springs 52, the collar 57 will be projected until it strikes roller 38 and swings the lever 37 sufficiently for separating the contact blocks 36 and breaking the circuit 34. Immediately upon breaking the circuit, the armature 27 is released and spring 32 draws the lever 25 to its upper position, thus locking the respective hub 3 and corresponding knob. Obviously, as the projection 29 only acts on the one hub, an operator from the inside may retract latch 8 by manipulation of the inner knob. When the train again starts and the weights 46 begin to move outwardly 130

by centrifugal force, the collar 57 will be retracted and lever 37 will be drawn over by spring 37' until the blocks 36 are again brought in contact, which, restoring the circuit, energizes magnets 28 and draws down lever 25, releasing the hub 3 and leaving the respective knob in condition for manipulation of the latch.

What we claim is,—

1. In a device of the class described, the combination with a car door lock, electrical means for controlling the same, a circuit for said electrical means, a switch for said circuit, and a car axle, of a governor connected with and actuated by the axle, an annular member surrounding the axle and shiftable bodily longitudinally thereof and connected to rotate therewith, connections between the annular member and governor for transmission of bodily movement to the annular member from the governor relative to rotation of the axle, and a lever for said switch extending into the path of bodily movement of the annular member and adapted at times to be struck and operated thereby.

2. In a device of the class described, the combination with a car door lock, electrical means for controlling the same, said electrical means maintaining the lock in condition for manipulation during the supplying of current to the electrical means, a circuit for said electrical means, a switch for said circuit, and a car axle, of a governor connected with and actuated by the axle, an annular member surrounding the axle and shiftable bodily longitudinally thereof and connected to rotate therewith, connections between the governor and annular member for imparting bodily movement to the annular member from the governor relative to rotation of the axle, and a lever for said switch extending into the path of bodily movement of the annular member and adapted at times to be struck thereby for opening said circuit.

3. In a device of the class described, the combination, with a car door lock, electrical means for controlling the same, a circuit for said electrical means, a switch for said circuit, and a car axle, of a governor connected with and actuated by the axle, an annular

member surrounding the axle and adapted to be shifted bodily longitudinally thereof by the governor relative to rotation of the axle, a lever for said switch extending into the path of bodily movement of the annular member, and a roller carried by said lever and adapted to be engaged by the annular member during one portion of its bodily movement.

4. In a device of the class described, the combination, with an axle, of a collar fixed to the axle and revolving therewith and having an under-cut groove extending parallel to the longitudinal axis of the axle, a slide bar fitted in said groove and retained by the overhang of the groove against lateral play, a governor arm carried by the collar and connected to the slide bar for imparting longitudinal thrusts thereto relative to movement of the axle, and lock controlling means actuated by said slide bar.

5. The combination, with a rotary shaft, of a collar fixed to revolve therewith, a centrifugal governor carried by said collar, a slidingly mounted bar carried by said collar, connections between the bar and governor for shifting the bar longitudinally relative to movements of the governor, an annular collar fixed to said bar and loosely surrounding said shaft, and a lock controlling circuit breaking lever extending into the path of movement of said last mentioned collar.

6. In a device of the class described, the combination, with a revolute element, of a weighted governor arm pivotally connected thereto and having a concave recess, the recess portion being slotted transversely, a convex washer fitted into said recess, a bolt extending through said washer and slot, a retracting spring engaging the said bolt, an adjusting nut threaded on said bolt into engagement with said washer, and lock controlling means actuated by said governor arm.

In testimony whereof we affix our signatures in presence of two witnesses.
